United States Patent Office

Des. 193,205
Patented July 10, 1962

193,205

YARD LIGHT

Jimmie Marson, Rte. 2, Box 224, Wewoka, Okla.

Filed Jan. 29, 1962, Ser. No. 68,546

Term of patent 14 years

(Cl. D48—24)

FIG. 1

The rear of the yard light not shown is substantially the same in appearance as the front except as indicated in FIGS. 1 and 2.

I claim:

The ornamental design for a yard light, as shown and described.
